CHRISTIAN AALBORG, OF PITTSBURGH, PENNSYLVANIA, ASSIGNEE TO WESTINGHOUSE ELECTRIC & MANUFACTURING COMPANY, A CORPORATION OF PENNSYLVANIA.

SWITCH.

Application filed February 19, 1921. Serial No. 446,258.

To all whom it may concern:

Be it known that I, CHRISTIAN AALBORG, a citizen of the United States, and a resident of Pittsburgh, in the county of Allegheny and State of Pennsylvania, have invented a new and useful Improvement in Switches, of which the following is a specification.

My invention relates to switches and particularly to single or double-throw-knife-blade switches such as are commonly employed on structures for connecting terminals of high-tension circuits.

Switches of this type are usually devoid of operating handles and are provided with eyelets or various forms of latches adapted to be engaged by a "hook-stick" or operating rod for moving the switch blade in and out of contact with the jaws. In service, such switches are infrequently operated and remain in closed position for long periods of time, during which interval, due to oxidation and corrosion of the contacting members, the blades become fastened within the jaws with such security that it becomes necessary to pry them therefrom by suitable instruments, it being frequently impossible to dislodge them quickly by using the "hook-stick" in the usual manner. In cases of emergency, serious damage may result to machinery, or the life of an operator may be endangered, by reason of the sticking of the blade within the switch jaws when it is necessary to quickly open the circuit.

One object of this invention is to provide a switch wherein the use of a "hook-stick" in the usual manner causes the blade first to be positively pried loose from the jaws by the operating lever, after which operation the blade may be entirely withdrawn from the jaws with little effort.

Another object is to provide a switch having the above characteristics wherein the latch mechanism employed is of simple, compact and inexpensive construction and wherein vital elements are protected from contact with foreign objects.

Another object is to provide a double-throw switch wherein separate latching levers engage separate latches and wherein the latch levers are counterparts and, therefore, interchangeable.

A further object is to provide a switch-latching mechanism employing a minimum number of moving parts, the action of which

is positive under severe outdoor conditions. 55

A further object is to provide a switch latch designed primarily for double-throw switches, which is inexpensive and may be used for single-throw switches without necessitating any change in design. 60

These and other objects are attained by means of switch apparatus embodying the features herein described and illustrated in the drawings accompanying and forming a part hereof, wherein:— 65

Fig. 1 is a side elevation of the improved switch apparatus, showing the blade in two operative positions.

Fig. 2 is a plan view of the operating levers showing them in assembled relation. 70

Fig. 3 is a side elevation of one of the operating levers showing the inner side thereof, with the position of the co-operating lever indicated in dot-and-dash lines.

Referring to the drawing, the switch includes pivot-jaw member 5 and two pairs of contact jaws 6 and 7, all of which are supported upon insulated bases or pedestals 8 which are preferably secured to a switch base 9. The pivot clip 5 is provided with a terminal 10 which, for the purpose of illustration, may be considered as connected to a bus-bar receiving current from a generator (not shown). The contact jaws 6 and 7 are provided with terminals 11 and 12, respectively, which, it will be assumed, are connected to leads of two separate service circuits. 75

The service circuits are adapted to be separately connected to the bus-bar by means of a knife-switch blade 13 which is pivoted to the pivot jaw 5 and is adapted to be swung into operative engagement with the contact jaws 6, as shown in full lines of Fig. 1, or into operative engagement with the contact jaws 7, as indicated in dot-and-dash lines in Fig. 1. The jaws 6 and 7 are of the split or jaw type well known in the art in which a pair of contact strips are held in spaced relation and so aligned with the blade as to receive the blade in the space between them and make snug contact therewith. 95

Switches of this type are well known in the art and it is also a matter of common experience that the blades thereof become so corroded at the points of contact as to cause the blades to stick within the jaws and

resist the efforts of the operator to open the switch with a "hook-stick" operated in the usual manner. In order to obviate this difficulty and to apply a positive leverage to the blade sufficient to loosen it from fixed contact with the jaws, I provide the free end of the blade 13 with a pair of operating levers 14 and 15 which are pivoted on opposite sides of the blade by means of studs 16 and 17, respectively.

The levers 14 and 15 are counterparts and, therefore, interchangeable, the former being pivoted, as shown in Fig. 1, on the far side of the blade and the latter upon the near side thereof.

Referring to Figs. 2 and 3, each lever includes a side portion 18 having a marginal flange 19 extend entirely around the periphery thereof and having a section 20 of greater depth than the flange 19 adapted to extend over the end of the switch blade which lies in the space 21 between the flanges 19. The flange portion 20 is provided with a re-entrant lip or stop 22, which lies adjacent the end 23 (Fig. 1 of the drawing) and is adapted to engage the blade to limit the movement of the lever with respect thereto when the lever is moved to unlatched position during the opening operation of the blade.

The lever is also provided with an inwardly extending lug 24 which engages the end 23 of the blade 13 during the movement of the lever in the direction tending to move it into latching position with a stationary latch member to be hereinafter described.

The lever is provided with a pivot hole 25 through which the pivot studs are inserted in assembling the lever upon the blade, and the flange 19 is provided with a latch recess 25 having a latch-engaging face or tooth 26 so positioned with respect to the pivot stud that, when the hook 27 is engaged by the "hook-stick" and the lever 14 is rotated in a clockwise direction, the tooth rotates similarly in a direction away from the end of the switch blade.

Referring to Fig. 1, each of the jaws 6 and 7 is provided with stationary latch members 28 and 29 which, as shown, are riveted to the jaw base. These latches may be made as integral parts of the jaws and, for the purpose of the claims of this specification, may be considered as parts thereof or as separate stationary latch members. The latch members 28 and 29 are so disposed that they lie in planes on opposite sides of the blade and engage the levers 14 and 15, respectively, when the blade is moved into the jaws 6 and 7, respectively. Each latch member is provided with a recess 30 adapted to receive the tooth 26 of its respective operating lever so that the said tooth interlocks with a similar tooth 31 on the latch member.

The notched side of the latch member is

so rounded at 32, adjacent the free end thereof, that it will move over a similarly rounded edge 33 on the co-operating latch member in such manner that the latch lever will be so retracted as to clear the latch member when the blade 13 is moved into operative relation with the contact jaws.

The latch or operating levers 14 and 15 are normally held in the position indicated in Fig. 1 by means of a helical spring 34, one end of which is attached to the flange 20 of one lever, while the other end is attached to a similar flange on the other member. The spring lies within the space between the levers and is protected against contact with external or foreign objects by the housing formed by the operating levers. The spring constantly exerts a force tending to draw the lever hooks toward one another and their range of movement, in the direction in which the spring tends to draw them, is limited by means of lugs 24 which engage the end 23 of the blade 13.

It will be seen from the foregoing that, if a "hook-stick" were inserted in the hook 27 of the lever 14 and drawn outwardly in a direction tending to withdraw the blade from the jaws 6, the lever 14 would pivot upon the stud 16 and so move with relation to the blade as to disengage the teeth 31 and 26 of the latch member and lever, respectively.

The movement of the lever 14, with respect to the blade, is limited, however, by contact of the stop 22 with the end 23 of the blade and, when the stop 22 engages the end of the blade, the pull of the "hook-stick" is transmitted directly to the blade. As the latch lever is withdrawn at the time from the latch member, the blade is automatically released and may be withdrawn from the jaws, but, as has been previously pointed out, the blade frequently becomes so tightly fastened between the jaws that a direct pull on the lever 14 that would not injure it, would not be sufficient to start the movement of the blade.

I have, therefore, provided each of the levers 14 and 15 with a projection 35 that is adapted, when the lever is in latched position, to abut the extreme end of the latch member with which it co-operates in such manner that, when the lever is pulled in a direction tending to withdraw the blade, the projection 35 will fulcrum on the ends of its respective latch member and positively pry the blade outwardly and loosen it from the jaw by force and leverage greater than could possibly be exerted by a direct pull of the "hook-stick" that would not injure the lever or latch.

It will be seen from the foregoing that, when a blade is stuck within the jaws, the first unlocking movement of the operating levers, relative to the blade, forces the blade

loose from the jaws, after which operation, the blade may be withdrawn with ease by pulling on the "hook-stick" in the proper direction. The levers are normally held in 5 a predetermined relation with respect to the blade by the spring 34 and automatically snap into latched relation with its co-operating latch member when the blade is moved into operative relation with the jaws.

10 While I have shown the latch member as a portion of the jaw structure, it is obvious that it may be mounted in any convenient manner and may be incorporated in the jaw strips, and that the lever could fulcrum upon 15 any stationary member, not necessarily a part of the latch member, which might be joined to the jaws or be independent thereof, without departing from the spirit of my invention.

20 While I have described and illustrated but one embodiment of my invention, it will be apparent to those skilled in the art that various changes, modifications, substitutions, additions and omissions may be made in the 25 apparatus illustrated without departing from the spirit and scope of the invention as set forth by the appended claims.

I claim as my invention:—

1. The combination with a switch blade 30 and contact jaws therefor, of a stationary member, and an operating handle for the blade movably mounted thereon and provided with a portion that engages the stationary member to move the blade with respect to the jaws when the handle is moved with 35 respect to the blade in a direction tending to move the blade out of the jaws.

2. The combination with a switch blade 40 and contact jaws therefor, of a member associated with said contact jaws, and an operating lever for the blade movably mounted thereon and provided with a portion that engages said member to move the blade with respect to said jaws when the lever is moved 45 with respect to the blade.

3. The combination with a switch blade 50 and contact jaws therefor, of an operating lever for the blade movably mounted thereon and having an engaging portion that is locked relatively to the jaws when the blade is moved into operative position therein and which has means that move the blade with respect to the jaws when the lever is moved with respect to the blade.

55 4. The combination with a switch blade and contact jaws therefor, of an operating lever for the blade movably mounted thereon and having a portion that automatically locks relative to the jaws when the blade is moved into operative engagement with the 60 jaws and which has a portion that moves the blade with respect to said jaws when the lever is moved with respect to the blade and out of locked relation with the jaws.

65 5. The combination with a switch blade

and two contact jaws mounted for separate engagement by the blade, of a stationary member mounted adjacent to each contact jaw and a pair of operating levers pivoted to the blade for separately automatically engaging the stationary members when the blade is moved into operative engagement with the contact jaws for retaining the switch blade in contact therewith, the said levers being provided with a portion co-operating with the stationary members to move the blade with respect to said contact jaws when that lever which engages one of the said stationary members is moved with respect to the blade. 70

6. A switch comprising a pivot jaw member, a switch blade pivoted to the jaw member, two pairs of spaced contact jaws mounted for separate engagement by the switch blade, a pair of operating levers movably mounted on the blade, each being provided with means that automatically interlocks with a member on one of the pairs of jaws when the blade is moved into operative engagement therewith, yielding means connecting the levers to normally hold them in a predetermined position with respect to the blade, and cam means on one of the levers for imparting a starting movement to the 80 blade when the lever is being moved with respect to the blade. 85

7. The combination with a switch blade and contact jaws therefor, of an operating lever for moving the blade bodily and having a pivotal connection therewith, whereby the lever may be moved without imparting movement to the blade, and means co-operating with the said lever when the blade is in operative engagement with the jaws whereby the blade is caused to be moved with respect to the jaws when the said lever is moved with respect to the blade. 90 100

8. The combination with a switch blade, a pair of contact jaws and a latch member, of an operating lever for the blade, movably mounted thereon and provided with means that co-operates with the latch member to hold the blade in operative relation to the jaws and with means that engages a fixed portion of the switch to move the blade with respect to the jaws when the lever is moved with respect to the blade. 110 115

9. The combination with a switch blade and a pair of contact jaws having a latching means, of an operating lever for the blade movably mounted thereon and having a portion that co-operates with the latching means to move the blade with respect to the jaws when the lever is moved with respect to the blade. 120 125

10. In combination, in an electric switch, a switch blade pivotally supported adjacent to its one end and having its free end adapted to frictionally engage a stationary contact member, and an operating lever piv- 130

oted on the blade intermediate its ends and having a portion thereof adapted to engage a fixed member to force the blade out of engagement with the stationary contact member when the operating lever is rotated on its pivot.

11. In combination, in an electric switch, a stationary contact member, a switch blade pivotally supported adjacent to its one end 10 and having its other end adapted to frictionally engage the stationary contact member, a cam member pivotally supported on the blade member, and a fixed member in position to be engaged by the cam member 15 when said member is rotated on its pivot, whereby the blade may be forced out of engagement with the stationary contact member.

12. In an electric switch, the combination

with a stationary contact member, a movable 20 contact member pivoted adjacent to its one end and, at its other end, adapted to engage the stationary contact member, and an operating lever pivotally supported on the movable contact member, said operating 25 lever being pivoted intermediate its ends and having one end adapted to effect a camming engagement with a fixed member and its other end serving as a handle whereby the said operating lever may be rotated about 30 its pivot to force the movable contact member out of engagement with the said stationary contact member.

In testimony whereof, I have hereunto subscribed my name this 15th day of February, 1921.

CHRISTIAN AALBORG.
